PORTABLE MUSICAL INSTRUMENT AMPLIFIER

John E. Demaree, South Pasadena, Calif., assignor to
Estey Electronics Company Incorporated, Torrance,
Calif., a corporation of Delaware

Filed Feb. 10, 1964, Ser. No. 78,563

Term of patent 14 years

(Cl. D26—14)

Fig. 1

Fig. 2

*Fig. 3**Fig. 4*FIGURE 1 is a front, top and right side perspective view of a portable musical instrument amplifier, showing my new design;

FIGURE 2 is a left side elevational view, to a reduced scale;

FIGURE 3 is a top plan view; and

FIGURE 4 is a rear elevational view thereof.

The dominant features of my new design are shown in solid lines in the drawing. The figures are stippled to indicate contrast in appearance, the stippling being continuous within the boundaries shown.

I claim:

The ornamental design for a portable musical instrument amplifier, as shown and described.
